PHONOGRAPH PICKUP CARTRIDGE OR SIMILAR ARTICLE

Duane E. Punkar, Conneaut, Ohio, assignor to The
Astatic Corporation, Conneaut, Ohio, a corporation
of Ohio

Filed Aug. 21, 1959, Ser. No. 57,248

Term of patent 14 years

(Cl. D26—14)

FIG. 1

FIG. 2

Fig. 1 is a perspective view of a phonograph pickup cartridge or similar article, showing the bottom, side and end of my new design;

Fig. 2 is a top plan view, to an enlarged scale, a portion being broken away for convenience in illustration, the bottom being substantially a mirror image thereof; and

Fig. 3 is a side elevational view, to an enlarged scale, a portion being broken away for convenience in illustration, the opposite side being substantially a mirror image thereof.

I claim:

The ornamental design for a phonograph pickup cartridge or similar article, as shown and described.
